UNITED STATES PATENT OFFICE.

JOHN A. MCGREW AND JAMES T. LOREE, OF ALBANY, NEW YORK.

SUPPORTING FRAME FOR HORIZONTAL RECIPROCATING ENGINES.

Application filed May 7, 1923. Serial No. 637,324.

To all whom it may concern:

Be it known that I, WILLIAM J. LUTTON, and JAMES T. LOREE, both citizens of the United States, and residents of Albany, county of Albany, and State of New York, have invented certain new and useful Improvements in Supporting Frames for Horizontal Reciprocating Engines, of which the following is a specification.

10 This invention relates to an improved supporting frame for horizontal reciprocating engines and in its broader aspects comprehends the provision of an improved frame structure particularly designed for use in connection with auxiliary or booster motors for locomotives whereby the engine or motor may be conveniently mounted and adequately supported upon and between spaced load bearing axles of a railway carriage or truck. 15 More particularly, our present improvements provide an engine supporting frame in the form of a single one-piece casting provided at its opposite ends with bearing parts for engagement with the spaced axles 20 and having means for the compact mounting and arrangement of the sliding cross-heads connected with the engine pistons and the drive gearing for transmitting motion to one of the truck axles. It is also an important 25 feature of the invention to provide an engine supporting frame of such construction that an automatic pressure actuated control valve for entraining the motor with the axle and governing the supply of steam to the motor cylinders may be detachably mounted in 30 operative position so that when necessary it may be readily removed without completely dismantling the engine.

35 It is a further general object and purpose of our invention to provide a supporting frame for booster motors of the horizontal reciprocating type which provides a properly balanced support for the engine, is of very substantial construction and enables the working parts of the engine to be properly housed and protected.

40 With the above and other objects in view, the invention consists in the improved supporting frame for the engine or motor, and in the form, construction and relative arrangement of its several parts as will be hereinafter more fully described, illustrated in the accompanying drawings and subsequently incorporated in the subjoined claims.

45 In the drawings wherein we have disclosed one practical and satisfactory embodiment of

the invention and in which similar reference characters designate corresponding parts throughout the several views:

Figure 1 is a fragmentary top plan view 50 showing one-half of the engine or motor and its supporting frame;

Figure 2 is a longitudinal central section taken on the line 2—2 of Figure 1;

Figure 3 is a longitudinal section taken on 65 the line 3—3 of Figure 1;

Figure 4 is an enlarged detail section illustrating the mounting and arrangement of the control valve; and

Figure 5 is a horizontal section taken on 70 the line 5—5 of Figure 4.

In the embodiment of the invention which we have selected for purposes of illustration, we have shown the engine or motor and its supporting frame mounted and arranged 75 upon and between the spaced axles 5 and 6 respectively, of a railway truck. It will be understood that in so far as our present improvements are concerned the booster motor or engine may be arranged for operation in 80 connection with the pilot or trailer truck of the locomotive, the tender truck, or one of the carriages or coach trucks. The several parts of the motor or engine whereby power is transmitted to one of the truck axles are 85 carried as a complete motor unit upon a single frame structure so that this motor unit with all parts assembled, together with its frame, may be mounted or arranged in operative position upon the truck axles or 90 removed therefrom in a single operation.

As herein shown, the supporting frame includes lateral or side portions 7 which are of identical form and construction, each of said side portions having a longitudinally 95 extending channel 8 to the base wall of which the parallel guide-ways 9 for one of the engine cross heads 10 are suitable secured. At one end, this cross head receiving channel communicates with a relatively deep chamber 11 formed in the frame structure which accommodates the connecting rod 12 which connects the cross head 10 with a counterbalance 13 fixed upon one end of the drive shaft 14. This drive shaft is journaled in 100 suitable bearings 15 formed upon the inner side walls of the chambers 11 and extends transversely of the frame structure above the transverse web or wall 16 which integrally connects the side portions of the 110 frame structure 7 at one of their ends to each other. A vertical wall 17 is formed at

the inner edge of the transverse web 16 and at its opposite ends is integral with the longitudinally extending webs or walls 18 which are connected at their lower edges 5 by a base wall 19 with the side portions 7 of the frame structure.

Upon the transverse end walls 20 of the frame which close the chambers 11 the bearing sections 21 are formed and are adapted 10 for engagement upon the upper sides of the truck axle 6. The lower halves 22 of these bearings are then applied and securely bolted to the frame structure as seen in Figure 3 of the drawings.

15 Between the two axle engaging parts 21 of the frame structure, the transverse end walls 20 are integrally connected at their upper ends by the bar 23 upon which is formed the upper housing section 24 for the 20 gear 25 on the axle 6. The lower housing section 26 is securely bolted to the section 24 and to the transverse frame web 16 as seen in Figure 2 of the drawings.

At their other ends the lateral or side 25 portions 7 of the frame structure are integrally connected by the vertical transverse wall 27 which is formed at its upper end with a longitudinally projecting horizontally disposed arm 28, the extremity of 30 which has a pivotal or rocking seat 29 centrally positioned over the axle 5 upon the leaf suspension springs 30 which are mounted at their ends on the spaced axle bearings 31.

35 The engine cylinders 32 are carried by opposite ends of a transversely positioned beam extending under the horizontal frame arm 28, said beam being also provided with steam distributing valve chambers leading 40 to the respective cylinders. The cylinders and the connecting beam are rigidly mounted upon the vertical frame wall 27, as by means of the bolts 33, the steam inlet nipple 34 communicating with the distributing valve 45 chambers being positioned through an opening in the frame wall 27, as shown in Figure 2 of the drawings.

The gearing for entraining the drive shaft 14 with the truck axle 6 includes a transmission gear element mounted in a frame 50 having spaced bearings loosely engaged 35 on the drive shaft for turning or rocking movement. The supply of steam to the engine cylinders and the entrainment of the drive shaft with the axle is controlled 55 through the medium of a steam pressure actuated valve generally indicated by the numeral 36. As herein shown, the casing of this valve is formed on one side with oppositely projecting flanges 37. The wall 17 60 of the frame structure has a relatively thick portion formed with a rabbet 38 at its upper edge in which ribs or tongues 39 on the upper edges of the flanges 37 are seated. 65 Each of the flanges is rigidly secured to

the wall 17 by the bolts 40. At its lower end the valve cylinder or casing is provided with the oppositely projecting inlet and outlet connections 41 and 42 respectively. Steam is supplied from the locomotive 70 power plant through the pipe 43 which is suitably coupled to the inlet connection 41 of the valve cylinder and the outlet connection 42 thereof is connected with the inlet nipple 34 leading to the steam distributing 75 valves by means of the pipe section 45, suitable fluid tight couplings being provided between the ends of this pipe section, the outlet connection 42 of the valve cylinder and the steam inlet nipple 34. 80

The steam distributing valves 46 which control the admission of steam to the engine cylinders 32 are actuated by means of the bell cranks 47 mounted upon the base plate 85 of the frame structure between the lateral or side portions 7 and the longitudinally extending webs 18 thereof, said bell cranks being actuated by the rods 48 connected to straps engaged with eccentrics 49 on the drive shaft 14. 90

The working parts of the engine or motor mounted upon opposite sides of the frame structure are substantially enclosed within 95 housings formed by the frame, the upper sides of these housings being closed by the cover plates 50. These cover plates rest upon the vertical flanges or walls of the frame structure and extend inwardly upon the vertical webs or walls 18, said plates being bolted, riveted or otherwise secured 100 upon the walls of the frame structure. At one of their ends, these cover plates are integrally connected by a transversely extending part 50', which as shown in Figures 1 and 2 of the drawings, extends over the 105 entrainment gearing, thus providing a substantially closed housing in conjunction with the transverse web 16 and vertical wall 17 of the frame whereby the gear parts are likewise protected against possible injury. It 110 will be apparent therefore that dust, grit or other foreign matter cannot collect upon the working parts of the mechanism and cause undue wear thereof or interfere with 115 their proper operation. 115

It will be seen from the foregoing description that in the improved frame construction, we provide for the very compact arrangement of the several parts of the booster motor or propulsion unit and are also enabled to readily mount the automatic pressure actuated control valve in position for proper operation of the entrainment mechanism and whereby said valve is easily accessible so that it may be readily removed 120 for inspection or repair when necessary. The supporting frame structure for the several parts of the booster motor being produced in the form of a single casting 125 which is of symmetrical construction, as 130

sures an equal distribution of the suspended weight between the spaced truck axles. This one-piece construction of the frame also precludes the possibility of relative dis-

5 placement of the working parts which might be caused by the loosening of connecting bolts or the shearing of rivets employed in connecting separate parts of the frame structure to each other.

10 We have herein shown the exhaust connection 51 from the engine cylinders having a pipe or conduit 52 coupled thereto which may extend to a second booster motor or propulsion unit whereby the latter is 15 operated by a further expansion of the steam.

We do not herein claim the broad idea of a motor of this character mounted upon a supporting frame suspended between spaced 20 truck axles, as this subject matter is fully claimed in our prior Patent No. 1,412,250, issued April 11, 1922. Likewise, no claim is made in the present application to the means for effecting entrainment between 25 the booster motor and the driven axle, or the pressure actuated control valve per se, as the former is disclosed and claimed in our issued Patents Nos. 1,447,352 and 1,447,353 of March 6th, 1923 and said control 30 valve is described and claimed in a co-pending application for patent filed January 6th, 1922, Ser. No. 527,302. Further we do not claim herein the broad idea of operating such a booster motor by steam 35 supplied from the locomotive boiler and automatically controlling its effective operation by the pressure of such steam, since such broad combination is described and claimed in a second co-pending application 40 for patent filed by us on December 15, 1921, Ser. No. 522,525. It will, therefore be understood that the novel subject matter of 45 the present application resides solely in the improved features of the one-piece supporting frame structure and the manner in which the several parts of the booster motor and the control valve therefor are supported and arranged upon this frame structure. In this respect, we believe that our present 50 improvements are of considerable practical importance in the art and provide for the more efficient and reliable operation of horizontal reciprocating engines or auxiliary propulsion units of this type.

55 While we have herein specifically described and illustrated an embodiment of the invention which we have found to be thoroughly practical and satisfactory in actual use, it is nevertheless to be understood that the essential features of our present improvement might also be exemplified in numerous other alternative structures and we accordingly reserve the privilege of adopting all such legitimate changes in 60 the form, construction and relative arrange-

ment of the several parts as may be fairly embodied within the spirit and scope of the invention as claimed.

I claim:

1. A motor supporting frame structure 70 consisting of a one-piece integral casting having lateral or side portions constituting housings for working parts of the motor, said side portions of the frame structure at one of their ends being integrally connected 75 with a central longitudinally projecting arm adapted to be mounted upon a truck axle and said frame structure at its opposite end having bearing parts for engagement upon a second truck axle. 80

2. A motor supporting frame structure having lateral side portions constituting housings for working parts of the motor, said frame structure having transversely extending parts integrally connecting said 85 housings with each other and provided at its opposite ends with bearing extensions adapted for engagement upon spaced truck axles, and cover plates closing the upper sides of the housings of said frame structure. 90

3. A motor supporting frame structure consisting of a one-piece integral casting having lateral or side portions formed to provide housings for working parts of the 95 motor, said side portions at one end of the frame being integrally connected by a longitudinally extending horizontal arm adapted to be mounted upon a truck axle, the cylinders of the motor being mounted and supported upon the part of the frame structure connecting said arm with the side or lateral portions of the frame, and bearing extensions at the other ends of said side portions of the frame structure for engagement upon 100 a second truck axle. 105

4. A motor supporting frame structure consisting of a one-piece casting having lateral or side portions formed to provide housings for reciprocating cross-heads and 110 operating gear for steam distributing valves, said frame structure at its opposite ends being provided with bearing extensions adapted to be mounted and supported upon spaced truck axles, cover plates for said 115 housings, and a steam pressure actuated control valve removably mounted upon the frame structure between the lateral or side portions thereof.

5. In combination, a one-piece motor supporting frame casting having bearing extensions at its opposite ends adapted to be mounted upon spaced truck axles, said frame casting at the opposite sides thereof being formed with longitudinally extending 120 housings, a transversely positioned drive shaft mounted in the frame structure, steam receiving cylinders and steam distributing valves mounted upon one end of the frame casting, driving connections between the 125 130

- cylinder pistons and the ends of said drive shaft working in said longitudinal housings, operating connections between the drive shaft and said distributing valves mounted in said housings, gearing for entraining the drive shaft with one of the truck axles, and cover plates closing the upper sides of said housings having a transversely extending integral connection at one of their ends extending over said gearing.
6. In combination, a one-piece motor supporting frame casting having bearing extensions at its opposite ends adapted to be mounted upon spaced truck axles, said frame casting at the opposite sides thereof being formed with longitudinally extending housings, a transversely positioned drive shaft mounted in the frame structure, steam receiving cylinders and steam distributing valves mounted upon one end of the frame casting, driving connections between the cylinder pistons and the ends of said drive shaft working in said longitudinal housings, operating connections between the drive shaft and said distributing valves mounted in said housings, gearing for entraining the drive shaft with one of the truck axles, cover plates closing the upper sides of said housings having a transversely extending integral connection at one of their ends extending over said gearing and a steam pressure actuated valve detachably mounted upon the frame structure between said housings operatively connected to the entrainment gearing and controlling the supply of steam to the engine cylinders.
7. In combination, a one-piece motor supporting frame casting formed at its opposite sides with longitudinally extending housings and having a transversely extending web connecting the inner side walls of said housings and a vertical wall at one edge of said web, a transversely positioned drive shaft mounted in the frame structure above said web, a steam actuated motor mounted upon the frame structure and having working parts positioned in said housings and operatively connected to the drive shaft, gearing for entraining said shaft with one of the truck axles, a steam pressure actuated valve detachably mounted upon said vertical wall operatively connected to said gearing and controlling the supply of steam to the motor cylinders, and cover plates for the upper open sides of said housing having an integral connection at one of their ends extending over said entrainment gearing.
8. A motor supporting frame including spaced housings for working parts of the motor, each of said housings having a bearing at one of its ends for engagement upon an axle, and a single bearing arm supporting said housings at their opposite ends and adapted to be mounted upon a second axle.
9. A motor supporting frame including
- spaced housings for working parts of the motor, each of said housings having a bearing at one of its ends for engagement upon an axle, a single bearing arm supporting said housings at their opposite ends and adapted to be mounted upon a second axle, said housings being open at their upper sides, gearing arranged between said housings for transmitting power from the motor to one of said axles, and a cover plate extending over said gearing and closing the open sides of said housings.
10. In combination, a motor supporting frame having bearing extensions at its opposite ends and formed with longitudinally extending housings at its opposite sides, motor piston cylinders mounted upon one end of the frame structure, a drive shaft journaled in the frame structure, driving connections between the motor pistons and said shaft working in said longitudinal housings, and a motivating fluid control valve for the piston cylinders removably mounted upon the frame structure exteriorly of said housings.
11. In combination, a motor supporting frame having bearing extensions at its opposite ends and formed with longitudinally extending housings at its opposite sides, motor piston cylinders mounted upon one end of the frame structure, a drive shaft journaled in the frame structure, driving connections between the motor pistons and said shaft working in said longitudinal housings, means for transmitting power from said shaft to a driven part, said means including an element movable to and from its effective power transmitting position, and a fluid pressure operated valve removably mounted upon said frame structure exteriorly of said housings for shifting said element to power transmitting position.
12. In combination, a motor supporting frame formed with longitudinally extending housings at its opposite sides, motor piston cylinders mounted upon one end of the frame structure, a driving shaft journaled in the frame structure, driving connections between the motor pistons and said shaft working in said longitudinal housings, means arranged between the housings for transmitting power from said shaft to a driven part, a cover plate extending over said power transmission means and closing the upper sides of the housings, and a fluid pressure actuated valve controlling the effective operation of said power transmission means and removably mounted upon the frame structure exteriorly of said housings.
- In testimony that we claim the foregoing as our invention, we have signed our names hereunder.
- JOHN A. McGREW.
JAMES T. LOREE.
